UNITED STATES PATENT OFFICE.

GREGORY M. MULLEN, OF BALTIMORE, MARYLAND.

ROPE-CLAMP.

SPECIFICATION forming part of Letters Patent No. 529,933, dated November 27, 1894.

Application filed July 25, 1894. Serial No. 518,516. (No model.)

To all whom it may concern:

Be it known that I, GREGORY M. MULLEN, of Baltimore city, in the State of Maryland, have invented a new and useful Improvement 5 in Rope Clamps or Couplings, of which the following is a specification.

My invention is an improvement in rope clamps and consists in certain features of construction and novel combinations of parts 10 as will be hereinafter described and pointed out in the claims.

In the drawings—Figure 1 is a side view and Fig. 2 a longitudinal section of my clamp. Fig. 3 is a detail perspective view of the clamp 15 section, and Fig. 4 is a detail section on about line 4—4 of Fig. 3.

The clamp is shown as composed of the clamp section A and the case section B both being constructed as more fully described 20 hereinafter. The clamp section A is formed with a head a preferably in the nature of an angular flange and which has on its outer side an eye a' or similar device to facilitate its connection with a rope, chain, or other section. 25 From the inner side of said head project longitudinally the clamping jaws C the outer edges of which are tapered, and threaded gradually enlarging toward their juncture with the head so the case when screwed thereon 30 will tend to press the jaws together and clamp the rope between them.

The inner adjacent faces of the clamping jaws are toothed or serrated to bite the rope and these faces are specially formed to permit the insertion of the rope laterally between the jaws as distinguished from inserting said rope longitudinally. This is an important 35 feature of my invention and is effected by having the space between said jaws at one or both of its edges as wide or wider than the space between the clamping portions of such jaws so the rope can be placed alongside the space between the jaws and pressed laterally therein. This is preferably effected by tapering or flaring the space between the jaws 40 transversely forming a wedge shaped space into which the rope is pressed. This avoids the inconvenience of passing the rope longitudinally between the jaws and also renders

it practical to set the jaws normally closer 50 together than when the rope is inserted longitudinally and as a consequence permits an efficient clamping of the rope with a very slight compression of the clamping jaws.

The case is provided with a longitudinal 55 bore b to receive the clamping arms such bore being tapered longitudinally and threaded to fit and compress the jaws of the clamp section when the case is turned upon said clamp section as shown. This case is made of sufficient length to practically incase the clamping jaws and the portion of the rope held therebetween such case being arranged at one end to abut the head a of the clamp section when the parts are adjusted together 60 and being provided on its other end with a head b', small opening b² just sufficiently large for the passage of the rope being provided at such end of the case the latter thus completely incasing the clamping jaws and 65 the portion of rope clamped between them. 70

Having thus described my invention, what I claim as new, and desire to secure by Letters Patent, is—

1. In a rope clamp a clamping section 75 provided with jaws, and having the space between said jaws tapered or flared laterally and a compressor substantially as set forth.

2. A rope clamp composed of a clamp section having integral jaws the inner faces of 80 which are formed at angles inclining laterally whereby the space between said jaws is tapered laterally whereby the rope may be pressed laterally between said jaws, and a compressor upon said jaws substantially as 85 set forth.

3. In a rope clamp the combination of the clamping section having the jaws serrated or toothed on their inner sides and threaded on their outer sides and having the space 90 between said jaws tapered or flared laterally and the case threaded on said jaws and made of such length as to inclose said jaws and the portion of the rope held therebetween substantially as set forth. 95

4. The improved rope clamp substantially as herein described consisting of the clamping section having the head, the jaws ex-

tended therefrom threaded externally and having the space between said jaws tapered or flared laterally and the case section having a longitudinal threaded bore and turning 5 upon the clamping jaws one end of said case being arranged to abut the head of the clamping section and the other end being formed

with a head and having an opening for the passage of the rope substantially as and for the purposes set forth.

GREGORY M. MULLEN.
